UNITED STATES PATENT OFFICE.

WILL E. KELLER, OF LOS ANGELES, CALIFORNIA.

CONCRETE-MOLD FORM.

Application filed September 1, 1926. Serial No. 132,957.

This invention relates to continuously travelling mold forms for use in connection with the formation of monolithic concrete walls, columns, and floor beams of building structures.

A general object of this invention is to provide a continuously movable mold form for not only pouring the outer walls of a building structure, but in addition thereto forming the floor supporting columns, and at suitable intervals the floor beams connected to the columns, all monolithically.

Briefly, the invention disclosed herein consists of a continuously movable mold form similar to the one illustrated and described in my co-pending application entitled Concrete wall construction, Serial No. 127,739, filed August 7th, 1926, in which provision was made for pouring concrete bonding members during the pouring of hollow concrete walls, and also specifically described in U. S. Patent No. 1,566,135, issued December 15, 1925, to Clara W. Waugh entitled Wall bonding device, assigned in full to me. In this application I have altered the mold form construction in order to render possible the simultaneous pouring of concrete floor supporting columns with the outside walls, and at intervals the floor beams that are connected to the columns and walls, all in a monolithic manner. The alteration in the mold forms above referred to resides in providing suitable stationary or movable mold walls for the floor supporting columns, and transversely disposed bottom mold walls for the floor beams, together with removable supporting timbers for the floor beams, the side walls for forming the beams being of the same type as the outside movable mold forms to which they are connected and operate therewith. Provision is also made for inserting the necessary steel reinforcing rods and bonds during the pouring of the walls, although such reinforcements form no part of the present invention.

In the accompanying drawing wherein one embodiment of the invention is set out by way of illustration.

Fig. 1 is a plan view of a reinforced concrete building in process of construction, showing a plan view of a portion movable mold forms in position.

Fig. 2 is a detail perspective view of a portion of a concrete building structure un-

der construction showing the connection between one of the outer walls, the floor beams, and supporting columns, together with portions of the mold forms.

Fig. 3 is an enlarged detail sectional elevation of a portion of the building illustrated in Fig. 1 taken on line 3—3 of Fig. 1.

Fig. 4 is an enlarged fragmentary floor plan showing the arrangement of the mold forms for the side walls, floor supporting beams, and columns.

Fig. 5 is a fragmentary sectional elevation showing an outside wall, column, and floor beams with the reinforcing steel embedded therein, taken on line 5—5 of Fig. 4.

Fig. 6 is a detail section showing the manner of embedding the floor slab stirrups in the beams, taken on line 6—6 of Fig. 5.

Fig. 7 is a similar view showing the floor beams stirrups bent to engage a floor slab.

Fig. 8 is a sectional view through a column form showing the first step in the pouring of the walls of a building.

Fig. 9 is a similar view with the floor beam bottom mold wall supports in place.

Fig. 10 is a view similar to Fig. 9 showing the floor beam after it has been poured.

Fig. 11 is a sectional perspective view of the mold form for forming floor slab recesses in the outer building walls, the slab anchoring rods being shown bent within the mold form.

Fig. 12 is a view similar to Fig. 2, showing the modified mold form construction.

Fig. 13 is a vertical sectional view of the first step in the formation of the building walls and columns of the modified form.

Fig. 14 is a similar view showing the second step.

Figs. 15, 16 are similar views showing the travelling forms raised to the height for forming beams with the beam and column boards in position.

Fig. 17 is a detail view showing the method of attaching the end of the column mold boards to the walls of the travelling forms, in the modified form.

In the drawings 10 designates the continuously movable forms, consisting of vertical side walls 11 for forming the outside hollow walls 12 of the building structure, and similar inner vertical walls 13, 14, for forming the floor beams. A mechanism for elevating the forms as the work of pouring

- progresses is shown at 15, the form members being provided with the usual horizontally disposed platforms 16 for use of the workman engaged in pouring the concrete.
- 5 In the various drawings although the outside walls are illustrated as hollow, consisting of a pair of wall members 17, 18, bonded together with concrete bonds 19, it will be understood that a single wall may be formed if desired, in such case the movable form is constructed with a single mold cavity.

The vertically disposed mold walls 13 for forming the transverse building beams 20 are arranged in pairs spaced an equal distance apart, as shown in Fig. 1, and similar mold walls 14 arranged in pairs also spaced apart for forming the longitudinally extending building beams 21 are connected thereto, all being rigidly connected to the vertical mold walls 11 of the movable mold forms and acting therewith. The beam mold walls are braced in the same manner as mold walls 13.

At the juncture of the transverse and longitudinally extending beam forming mold walls, are vertical walls 24, 25, 26, and 27 for forming the supporting columns of the building, best illustrated in Figs. 2 and 4 of the drawings. These mold walls for forming the beam supporting columns each consist of two sections —A— and —B— between the beams of each story of the building and are stationary with respect to the movable forms.

35 In erecting a building structure as illustrated herein the movable forms rest on the building foundation walls (not shown) with the lower sections —A— of the column forms in position as illustrated in the plan view (Fig. 4) as well as the sections —C— —D— which lie against the inner face of the outer hollow wall 12. Sections —C— —D— fill the space between the oppositely disposed mold walls 13 of the beam forming molds (see Fig. 2), and serve to confine the wet concrete within the outside wall mold form as the same is poured. Concrete is now poured to form the hollow walls as well as the columns 28, the movable forms being moved continuously as the walls and columns are poured. When the walls and columns reach a distance approximately one half of a building story the sections —B— of the column forms and the form sections 50 —D— are placed in position, the length of the sections —A— —B— and —C— —D— equalling the vertical distance between the floor beams. The pouring of the walls and columns is then continued until the lower 55 horizontal edges of the vertical walls of the movable form are in the position as shown in Fig. 9 when cross boards 31 are laid across the upper ends of the sections —B— and —D—, the boards forming with the movable 60 vertical mold walls 13, 14, beam bottom mold

walls, at the same time a number of vertically disposed bracing timbers 32 (4" x 4") are disposed under each cross bottom mold board, (see Fig. 2) designed to support the load of the floor beams 21 when poured, the timbers being removable as soon as the concrete has set a sufficient length of time.

After the cross boards have been placed in position other form sections —A— for the columns and sections —C— for the outer walls are placed in position, the lower ends of each of said sections being disposed a distance above the upper ends of the sections —B— and —D— equal to the thickness desired for the beams 21. The concrete from the inner wall member flows through the openings 33 into the beam mold forms to form the beam, and also through the four openings 34 leading from the beam molds to each column mold. The movable forms are continuously raised in the manner as hereinbefore described together with the beam and column molds until all the walls, beams and columns of the building have been formed, after which the forms —A— —B— —C— and —D— as well as the bracing timbers 32 may be removed from the finished structure.

The vertical walls of the building as well as the beams and columns all carry the usual steel reinforcing rods, and as such reinforcement forms no part of this invention, it is not thought necessary to describe the specific construction except in relation to reinforcing means for connecting the floors slabs (not shown) to the outer walls, beams, and columns of the building. This construction is best shown in Figs. 6 and 7, and preferably consists of a plurality of iron rods bent into stirrup form. The ends projecting above the upper faces of the beams being bent into a horizontal position as shown in Fig. 7 so as to engage the floor slabs when poured.

In order to provide for the attachment of the floor slabs to the inner faces of the outer walls of the building a horizontally disposed box form trough 35 is provided disposed directly above the upper faces of each series of floor beams. The hooked ends of reinforced rods 36 which are embedded in the inner wall member of the hollow wall member project into the trough 35, their ends being bent so as to not interfere with the movement of the vertical walls of the travelling mold forms.

In Figs. 12 to 17 inclusive another beam and column mold form construction is illustrated in which the column mold walls as well as the beam mold walls which lie against the inner surface of the outside building walls travel at certain times with the movable mold forms. By means of this construction it will only be necessary to use two sets of column and beam mold boards.

In this construction the movable wall,

beam, and column mold forms are exactly the same as in the forms heretofore described, with the single exception that the outside building wall forms are constructed 5 for forming a single instead of a hollow wall. The column mold walls each consist of two sets —A'— and —B'—, and the mold wall boards used at the juncture of the beams with the outside building walls also 10 consist of two sets —C'— —D'—. As the travelling mold forms for the beams and outside walls are the same construction and operate in the same manner as the first described forms the same reference numerals 15 are applied to similar parts in order to prevent confusion.

The manner of using the column and beam mold walls —A'— —B'— —C'— —D'— is best explained by reference to Figs. 13 to 17 of the 20 drawings. In Fig. 13 the movable or travelling form is illustrated in its first position resting on the wall foundations with the column mold walls —A'— in position, their upper ends being temporarily secured to the 25 movable forms by nails 50 (see Fig. 17) so that the walls will move upwardly therewith as shown in Fig. 14.

When the movable forms reach the position shown in Fig. 15 where floor beams 20 should be formed, bottom mold beam boards 31 are placed in position in the same manner as in the first described form with the braces 32 in position to support the beam, see Fig. 12.

After the brace supports 31 are in place 35 the nails 50 are pulled in order to disconnect the walls —A'— from the forms, and wall boards —B'— are placed in position, their lower ends 51 being disposed above the upper ends of boards —A'— a distance equaling the thickness of a beam, the openings 34 permitting the concrete to flow therethrough to the beam molds, as in the first construction.

The travelling forms continue their upward movement until their upper edges are flush with the upper ends of the mold walls —B'— when the nails 50 are again employed to fasten the mold walls to the forms (see Fig. 17) so that they will move therewith up to the point where another beam is to be formed. It will be understood that the mold board —C'— and —D'— that lie against the inner face of the outer walls are manipulated in exactly the same manner. When 50 the lower edge of the travelling forms pass the upper ends of the mold boards —A'— —C'— the same will be released, and are used again in the same position as occupied by the boards —B'— —D'— in Figs. 15 and 16.

The recesses for the floor slabs are formed in exactly the same manner as in the first described form by short lengths of form boxes 35, with the metal attaching rods 36 in position. In this construction the recess form

boxes are placed at either side of the concrete beams in order not to weaken the outer building walls.

By carrying the mold boards with the travelling molds only two sets of boards will 70 be required, the positions of the boards —A'— —B'— and —C'— —D'— being reversed as the work progresses.

From the above description it will be apparent that the floor beams, and columns of 75 a concrete building may be poured simultaneously with the outer building walls and in a single continuous operation, thus making the entire building, with the exception of the floor slabs, one monolithic piece of concrete. 80

What I claim is:

1. A concrete mold form of the "slip form" type consisting of a plurality of vertical mold walls arranged in pairs for forming the outside building walls, a plurality of similar mold walls arranged in pairs and in cross formation between the first mentioned mold walls; said walls adapted to form the floor beams, and a plurality of mold walls at the meeting ends of the second mentioned mold walls for forming the beam supporting columns; said walls arranged to provide openings at the ends of the beam molds, whereby to permit concrete 90 to flow from the columns and outside wall mold forms to the beam mold forms during a concrete pouring operation. 95

2. A concrete mold form of the "slip form" type consisting of a plurality of vertically disposed mold walls arranged in spaced pairs for forming the outside building walls, a plurality of similar mold walls arranged in transverse and longitudinal formation between the outside mold walls and connected thereto, a plurality of column form walls, bottom walls for said beam mold forms, means to support said bottom walls in position, said beam mold forms having openings at their ends communicating with the outside walls and the column forms, whereby the outside walls, columns, and wall beams may be formed monolithically. 100 105 110

3. A concrete mold form of the "slip form" type comprising vertically disposed mold walls arranged in pairs and spaced apart for forming the outer walls of a building, a plurality of similar mold form walls for forming floor supporting beams connected to said outer mold walls, said last named mold walls arranged in crossed formation, a plurality of vertically arranged column mold walls engaging the oppositely disposed ends of each beam forming mold walls and having openings communicating with the beam molds, the ends of the beam molds also opening into the outer wall mold forms, bottom walls for said beam mold forms and means to support the same in position, and mold form walls disposed against the inner 115 120 125 130

faces of the outside building walls, the inner walls of the outer mold forms being slotted vertically for the reception of said mold form walls, whereby to permit movement of 5 the slip forms.

4. A concrete building form comprising a plurality of vertically disposed mold forms for forming the outer walls of a building structure, a plurality of similar mold forms 10 for forming floor supporting beams between the outer building walls, said forms extending longitudinally and transversely, said forms opening into the outer wall mold forms, and a plurality of column form 15 molds, said forms engaging the beam mold forms at the juncture of the cross beam forms and communicating therewith, and bottom walls for the beam mold forms.
5. A concrete mold form of the "slip 20 form" type comprising a plurality of pairs of vertical mold form walls for forming the outside building walls, beam mold forms extending between two of the oppositely disposed mold walls and movable therewith, a 25 stationary mold form for forming a beam supporting column, the oppositely disposed ends of the beam molds opening in the column molds and the ends of the beam molds abutting the inner face of the outside mold

walls opening into the same, whereby the 30 walls, beams, and columns will be formed in a single mass.

6. A concrete mold form of the "slip" type comprising a movable mold form for forming the outer building walls and the 35 floor supporting beams in a single mass, and means to move said forms as the concrete is poured.

7. A concrete mold form of the "slip" type comprising movable mold forms for 40 forming the outer building walls and the floor supporting beams between said walls, and forms for forming the beam supporting 45 columns connected to the movable beam forms.

8. A concrete mold form of the "slip" type comprising a movable mold form for pouring the outside walls and floor supporting beams in a single continuous operation, and other mold forms connected to the beam 50 portions of said first named forms for pouring beam supporting columns, the walls, floor beams, and beam supporting columns all being formed monolithically.

In witness that I claim the foregoing I 55 have hereunto subscribed my name this 6th day of August, 1926.

WILL E. KELLER.
